UNITED STATES PATENT OFFICE.

W. JAY KETCHAM, OF WASHINGTON, DISTRICT OF COLUMBIA, ASSIGNOR
TO HIMSELF AND GEORGE S. PRINDLE, OF AURORA, ILLINOIS.

IMPROVEMENT IN RETAINERS FOR NECKTIES.

Specification forming part of Letters Patent No. 76,468, dated April 7, 1868.

To all whom it may concern:

Be it known that I, W. J. KETCHAM, of Washington, in the District of Columbia, have invented an Improvement in Necktie-Holders; and I do hereby declare that the following is a full, clear, and exact description thereof, reference being had to the accompanying drawings, making a part of this specification, in which—

Figure 1 is a plan view. Fig. 2 is a longitudinal cross-section. Fig. 3 is a view of the necktie and holder combined.

Letters of like name refer to like parts in each of the figures.

A represents the frame, curved to fit the neck, made of brass, steel, or other metals, or of any flexible material, such as parchment, pasteboard, &c. When of the latter, however, it will be necessary to attach a spring to give sufficient elasticity and enable it to retain its form.

B B represent the catches for attaching the holder to the button fastening the front of the collar. They are made of steel, brass, or other metals, and fastened to the frame at C C, allowing the ends to meet at D, where each is notched, between which sufficient space is left to contain the thread fastening the button to the cloth.

This holder may be made of one piece, if desired, the ends of A being prolonged and bent over so as to form the catches B B.

The operation of this holder is very simple. By straightening the frame A the catches B B are separated at D, allowing them to pass over the button as the holder is placed in position, when upon releasing the frame A it resumes the curved form, bringing the ends of the catches together and firmly clasps the button between the notches. To remove it the same process is necessary.

The advantages possessed by this holder over all others in use are that it is easier to place in position and less liable to be accidentally detached, it is more simple in construction, and can be produced at less cost.

What I claim as my invention, and desire to secure by Letters Patent, is—

The within-described retainer for neckties, consisting of the spring base or plate A and catches B B, the latter provided with slots D, and its ends meeting or overlapping each other, the whole arranged substantially as shown and described.

In testimony that I claim the foregoing I have hereunto set my hand this 19th day of February, 1868.

W. JAY KETCHAM.
